DOLL CRADLE

Filed June 21, 1948

UNITED STATES PATENT OFFICE

2,582,061

DOLL CRADLE

Clayton J. Niebuhr, Dearborn, Mich.

Application June 21, 1948, Serial No. 34,330

1 Claim. (Cl. 5—105)

1

My present invention relates to an improved doll cradle which because of its unique construction is simple to manufacture and may be sold either assembled, or knocked down. In the latter case, the head and foot boards being bored in manufacture will easily receive the connecting rods or bars and the base is quickly secured.

No tools are required in assembly and only glue is necessary to secure the parts in assembled condition.

In the accompanying drawings I have illustrated one complete example of the physical embodiment of my invention according to the best mode I have thus far devised, but it will be understood that various changes and alterations may be made in the exemplified structure within the scope of the appended claim.

In the drawings:

Fig. 1 is a top plan view of the assembled cradle.
Fig. 2 is a side elevational view.

Fig. 3 is an end elevational view looking at the footboard.

Fig. 4 is a sectional view at line 4—4 of Fig. 2.
Fig. 5 is a partial enlarged sectional view at line 5—5 of Fig. 3.

Fig. 6 is a detail sectional view at line 6—6 of Fig. 3 showing the assembly details between the head and footboard and the base.

Referring now to the drawings wherein I have illustrated the present preferred embodiment of my invention I employ the head board 2 and foot board 4 each having a curved rocker bottom edge 6 and rounded top 8, the head board being somewhat higher than the foot board.

The base 10 consists in a concavo-convex supporting plate the ends of which fit into the arcuate slots 12 in the head and foot boards.

As here shown I use 4 connecting rods or bars 14 having knobs 16 glued or otherwise secured and the rods extend through suitable aligned apertures in the head and foot boards, the ends 18 being threaded at 20 to receive the interiorly threaded knobs 22.

The outer pair of bars are longitudinally grooved to receive the edges of the base and it will be apparent that the cradle may be assem-

2

bled by glueing the base into the end boards, and the side edges of the base into the grooved bars.

The assembled cradle will prove sturdy in use despite the ease of assembly and may easily be dis-assembled for storage should the cradle be of sufficient dimensions to so warrant.

Obviously the component parts may be made of wood, metal or plaster or a combination and will provide pleasure to children.

10 Having thus fully described my invention what I claim as new and desire to secure by Letters Patent is:

A doll cradle comprising end boards having curved rocker bottoms and arcuate shaped slots 15 in the end boards inwardly of the rocker bottom, a base of arcuate formation having the ends thereof receivable in the arcuate slots in the end boards, a pair of connecting bars having longitudinally extending slots therein, carried by the 20 end boards at points slightly above the upper ends of the rocker bottom and the slots in said bars receiving the longitudinally extending edges of the bottom, a second pair of bars carried by the end boards and positioned under the bottom 25 to support the bottom in position and the ends of the bars extending through said end boards and means receivable on the ends of the bars to secure the bars in position.
